Specification of Letters Patent. Patented Nov. 11, 1913.

Application filed August 14, 1912. Serial No. 715,030.

To all whom it may concern:

Be it known that I, JOHN M. ROHLFING, residing at St. Louis, Missouri, and being a citizen of the United States, have invented 5 certain new and useful Improvements in Underframes, of which the following is a full, clear, and exact description, such as will enable others skilled in the art to which it appertains to make and to use the same, 10 reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings: Figure 1 is a bottom or worm's eye view of an underframe embodying my invention. Fig. 2 is a side view of the same. Fig. 3 is a fragmental enlarged top view partially in section. Fig. 4 is a section of the left hand side of Fig. 3 on the line 4—4. Fig. 5 is a continuation of Fig. 4 25 extending to the center of the car, the section line 4—4 extending beyond the second cross-number. Fig. 6 is a section on the line 6—6 of Fig. 4 showing the relationship of the center sill tension and compression members. Fig. 7 shows a section on the line 30 7—7 of Fig. 5 through the brake cross bar support. Fig. 8 is a section on line 8—8 of Fig. 4 showing the section of the tension member at that point. Fig. 9 is a section on 35 the line 9—9 of Fig. 4 looking in the direction of the arrow showing the relationship of the compression and tension members and the method of securing the bolster to the center sills on the line indicated. Fig. 10 is 40 a section on the line 10—10 of Fig. 4 showing the relationship of the tension and compression members and the cross bearer on the line indicated. Fig. 11 is a fragmental section on the line 11—11 longitudinally of Fig. 45 4 and laterally of Fig. 9 showing the method of attaching the cast tension member to the draft sills.

This invention relates to underframe construction for railroad cars, trussed sill construction, and comprehends broadly the use 50 of a relatively elastic compressible compression member and a relatively rigid tension member, and cross members associated with side and end sills suitably proportioned for 55 the designed construction and suitably

assembled to form a commercial under-frame.

In this particular art, since the bridge work that employed a compression member or top chord and an angle or rolled section 60 as a tension member or lower chord, the trend of the car builder has been to utilize a rigid top chord and an elastic or relatively elastic bottom chord. As the art advanced, this tendency has developed in the assemblage of a plurality of commercial sections 65 to form a relatively rigid structure as a compression member and a truss of relatively elastic construction to compensate and brace the rigid structure and to form a tension 70 member. Several inventors have departed from this usage and have employed cast center sill extending from end to end of the car underframe and comprising both compression and tension members or have formed 75 such cast center sills in sections suitably riveted together and in some cases have made the castings to include parts of the bolsters or cross members. The rigid cast underframe owing to the jar of track irregularity and the 80 buffing stresses tended to break the rigid connections between parts and have proved too rigid for general service underframes.

One of the greatest difficulties to be overcome in the construction of rolled metal section truss construction was the tendency under buffing stresses to buckle the car toward the center which though practically overcome by the deepening of the depending truss and the providing of a web between 85 the sills and the lower chord of the truss, this construction although the accepted practice construction, still lacks the rigidity necessary to resist the buffing stresses and is too 90 springy or whip-like in its action on recovery. This present invention while utilizing well-known principles employs those principles diametrically opposite to the accepted 95 practical usage by constructing the upper chord of the truss of a plurality of commercial rolled sections assembled in such manner as to constitute a relative elastic compression member and by utilizing a casting forming the lower chord of the truss, as a 100 rigid tension member. The casting is 105 formed preferably with the truss struts integral therewith and adapted to be placed in juxtaposition with and support the compression member.

To more particularly describe this present 110

invention, the compression member of the truss is preferably formed of commercial roller sections provided with a connecting cover plate and is supported upon the cast 5 truss member by means of suitable chairs in such manner that compression exerted upon the rolled section is absolutely resisted by the cast truss member bearings or chairs and yet the space between such chairs afford 10 sufficient resiliency on the part of the rolled section to permit of the maintaining of the relationship of the parts, that is, that of elasticity on the part of the compression member within its capability of resistance, 15 insofar as it is held or supported by the rigid tension member.

To more particularly describe this invention with reference to the accompanying drawings, the center sill is composed of the 20 compression member comprising a plurality of assembled commercial rolled sections which will be described more in detail hereafter and a tension member consisting of a casting comprising in the main a web 1 extending from one end to the other of said 25 castings and provided with a bottom flange 2 extending into the center plates 3 at each end of the castings, which are integral with the casting. The center plates 3 carry the 30 king pin socket, and also form a bolster filler and the walls of said center plates are supported by an extension of the web 1 of the casting extension beyond the king pin socket and by radially arranged webs 4 and 35 by the wall of the king pin socket. The center plate 3 is provided with vertical flanges 5 arranged to be fixed to the inside of the draft sills 6 and so arranged as to provide a recess into which the bottom flange of the 40 draft sill may fit. A horizontal side flange 7 is also provided which is adapted to support the bottom of the bolster casting 8.

At intervals along the casting are laterally extending vertical wings 9 integral with 45 the casting and provided at their outer end with vertical and horizontal flanges 10-11, the vertical flange being in a plane parallel with the web of the casting. Their flanges taken together form an angle support or 50 bracket and securing means for the cross bearers, it will be observed that the vertical and horizontal flanges lie in the same planes as the bolster securing and supporting flange 7. The casting or tension member is designed to be widest at its center and tapered 55 toward the bolster as is usual with the accepted truss shape. The upper portion of the casting is provided with a horizontal top flange forming a support for the compression member, the top of which flange extends 60 in the same plane as the top of the center plate 3, so that the superstructure or the compression member may be supported throughout its length. The web 1, of the

casting may be cut away at intervals from 65 the upper portion thereof for lightness and the periphery of the openings thus formed reinforced by flanges 14, thereby forming from the upper flange of the tension member, compression member chairs 13 which are 70 supported on the portions of the web which are not cut away and which might be termed struts 1^a. The compression member comprises a pair of commercial channel sections 75 spaced apart and arranged back to back. These commercial channel sections extend through the bolsters abutting the ends of the draft sill 6 and with the draft sills form a continuous double center sill from end to end of the car. These commercial sections 80 are attached by their bottom flanges 15^a to the compression member chairs 13 and are secured together at their top by a cover plate 16 fixed to the top flanges 15^b, said cover plate extends beyond the bolster toward the 85 end sills and covers a part of and is fixed to the upper flange of the draft sill 6. The draft sills 6 extend from the center plate of the casting to the end sills and are adapted to carry the draft gear of the car. These 90 sills are attached to the tension member casting and the compression member sills by means of angle bars 17 within the said sills, the upstanding legs of the angle bars extending along the compression member 95 sills and being fixed thereto and the horizontal flange is adapted to be fixed to the tension member casting; i. e., the top of the center plate. Bolster castings 8 are identical, it taking two to form a complete bolster 100 and are arranged with a vertical central web and upper and lower flanges 18 and 19. The upper side of the bolster drops slightly from the horizontal plane at the outer end to provide a bracket for the Z-shaped side sill 20, 105 so that the top flange of said sill shall lie in the same plane as the center sill cover plate 16, an upwardly extending flange 21, having a bracing web 22 is provided as a side or inside support for the Z-shaped side 110 sill. The upper flange 18 of said bolster is provided with a seat 23 for the nailing strips shown in dotted lines in Figs. 9 and 10. The web and the upper and lower flanges of the bolster project beyond the 115 Z-shaped side sill and are cross braced by a vertical web 24. The lower flange of the bolster is perforated at its outer end to facilitate bolting and is provided with an integral body side bearing 25 and with a recess into which the horizontal flange 7 of the center plate 3 fits. The inner end of the cast bolster is recessed and the flange is arranged in two planes, the one to conform to the contour of the cast tension member and 120 to be affixed thereto, and the other to conform to the compression member and to be 125 affixed thereto. To more rigidly attach the

bolster parts together, a tie plate 26 extending through the channel sills of the compression member is rigidly fixed to the upper flange of the bolster sections, and the 5 walls of the compression member sills are strengthened at the tie plate for a considerable distance on either side thereof by means of an angle bar 27; the upstanding leg of which is secured to the inner side of the side 10 wall of the compression member and the horizontal leg to the top of the tie plate.

The cross bearers consist of pressed metal 15 diaphragms 28, provided with integral surrounding edge flanges on one side only, and said cross bearers are tapered from the center sill to the side sills, the broader side being adapted to be attached to the center sills. These cross bearers are provided with a recess on the inner side, and the flange 20 thereof is arranged in two planes to fit the conformation of the center sill. Two of these cross bearer sections form a cross bearer and are interchangeable. Each pair of cross bearers is attached to the flanges 25 10-11 or brackets extending from wings 9 on the casting and also are attached to the vertical webs of the channel sections of the compression member. The upper flanges of the cross bearer are connected through 30 channel sections of the compression member by means of a penetrating tie plate 29 which is secured to the angle bars 30, shown in Fig. 10, which angle bars are riveted to the webs of the channel sections of the compression 35 members. The outer ends of the cross bearers are connected to the Z-shaped side sills by means of tapered angle brackets 31, which are provided with inclined reinforcing web and with an upstanding flange 32, 40 to which latter the Z-shaped side sill is attached.

It will be observed that the cross bearers next the bolsters have the flanged side turned inwardly or away from the bolsters, 45 and the next two members have the flanged side turned outwardly or toward the bolsters, and that the struts carrying these members project farthest in the direction of the flanged side of the cross members. 50 This arrangement is provided so that the end strains or the buffing strains may be better resisted.

Another important detail relative to this construction is that the weight of the car 55 body, the bolster sections and the cross-member sections 28, owing to the projecting brackets 9 and the center casting flanges 7, are carried upon the cast tension member and exert only a very slight side compression 60 force upon the compression member walls 15, should the car be submitted to any torsional strains on either side of the center sill. This is mainly due to the elasticity of the metal of the rolled metal cross members 28.

It will therefore be seen that the whole underframe is supported by the cast tension member and that the relatively elastic compression member is disposed in line to primarily receive and absorb buffing shocks.

The end sills of the car are of usual construction with the exception that the diagonal brace extending from the corner formed by the juncture of the Z-shaped side sills to the corner formed by the juncture of the bolster and center sills are omitted and angle 70 corner plates 34 and 35 are provided. These corner plates have upstanding flanges for securing the same to the end and side plates and are only used at the juncture of the Z-shaped side sills and the end sills, and the juncture 75 of the center draft sills and the end sills.

Means are provided for securing brake beam levers in position on the cast metal member, said means comprising sockets 3^a and clips 3^b. Through the clips 3^b and projecting into the sockets extend pins 36, 80 which are adapted to be projected through the usual pivot bearings in brake levers, and the cotters 36^a hold said pins 36 in position.

By this construction the entire lower or 90 tension part of the underframe is rigid or as rigid as cast metal can make it, and the bolsters are rigid and every part is so shaped and arranged that all compression strains shall be exerted upon a relatively elastic 95 element compression member which is reinforced and carried by the cast tension member, also every part between the bolsters transmits its weight to the cast tension member so that the elasticity of the compression 100 member is limited in its vibration by the supporting or tension member.

A point to be observed in this device is that the draft sills and end construction of the underframe are composed of rolled sections and light as compared with the main resisting and carrying tension member so that should any great buffing stress be brought to bear upon the end sills or end sections, as a collision, it could only buckle 110 or collapse the end section until the main resisting column or back-bone was reached. This arrangement practically protects the body of the car by sacrificing the platform. Such a contingency, however, would be rare 115 as the end frame construction used in this application is as strong, if not stronger, than those in general use at present. The main idea of this construction is that all strains from whatsoever source, are transmitted to a rigid supporting tension member 120 and primarily transmitted in all directions to the relatively elastic compression member. Said compression member of the center sill is illustrated as being formed of 125 spaced rolled channel-shaped sections connected by means of a top cover plate, though it is evident that other commercial sections

may be substituted therefor and be connected in various ways within the spirit of the present invention.

What I claim is:—

- 5 1. In an underframe for railroad cars, a sill comprising a cast tension member and a compression member formed of a plurality of rolled commercial sections and transverse members supported by said sill.
- 10 2. In an underframe for railroad cars, a sill comprising a cast tension member and a compression member composed of assembled rolled commercial sections and transverse members supported by said sill.
- 15 3. In an underframe for railroad cars, a sill comprising a cast tension member and a compression member composed of a plurality of rolled commercial sections and transverse projections extending from the 20 cast tension member and transverse members carried by said projections.
4. In an underframe for railway cars, a compound center sill comprising a cast tension member and a compression member composed of a plurality of rolled sections, 25 said compression member being fixed to and supported by said tension member and transverse members supported by said center sill.
- 30 5. In an underframe for railway cars, a center sill comprising a tension member of cast metal and a hollow rolled metal compression member and transverse members supported by said center sill.
- 35 6. In an underframe, a truss center sill comprising a plurality of commercial rolled sections forming the upper chord of a truss and a casting provided with struts adapted to support the upper chord of the truss, 40 forming the lower chord of the truss and transverse members supported by said center sill.
- 45 7. In an underframe, a truss center sill comprising a plurality of rolled commercial sections forming the upper chord of a truss and a casting forming the lower chord of a truss and transverse members adapted to absorb the strains of torsion and compression connecting the members of said center 50 sill.
- 55 8. In an underframe, a truss center sill comprising a plurality of rolled commercial sections forming the upper chord of a truss and a casting forming the lower chord of a 55 truss, and transverse members connecting the members of the central sill, and connected together through the center sill and adapted to absorb the strains of the torsion and compression of the load above the 60 underframe.
- 65 9. In an underframe, a center sill comprising an integrally cast tension member extending beyond the bolsters and assembled 65 rolled commercial sections forming a compression member and extending from

end to end of the car and transverse members fixed to said center sill.

10. In an underframe, a center sill comprising an integrally cast tension member extending beyond the bolsters and assembled 70 rolled commercial sections forming a compression member and extending from end to end of the car, bolsters, bolster bearings cast integrally with the tension member and projecting from the sides thereof, transverse 75 members intermediate of the bolsters and fixed to the said center sill.

11. In an underframe, a center sill comprising an integrally cast tension member extending beyond the bolsters and assembled 80 rolled commercial sections forming a compression member and extending from end to end of the car, bolsters, bolster bearings cast integrally with said tension members and cross bearers and cross bearer 85 brackets cast integrally with the tension member and projecting from the sides thereof.

12. In an underframe comprising the combination of bolsters, and cross members, 90 of a trussed center sill comprising a compression member formed of a plurality of channel sections and a cast tension member formed with an integral flange as a bearing for said bolsters and with integral brackets 95 as a bracing for the cross bearers.

13. In an underframe for railway cars, a sill comprising a relatively elastic compression member in juxtaposition with a cast rigid tension member and transverse members 100 fixed to said construction.

14. In an underframe for railroad cars, in combination with side sills, bolsters and cross members of a center sill comprising a cast tension member supporting the bolsters and cross bearers, and a compression member 105 formed of a plurality of rolled commercial sections in compression between the load above the underframe and the underframe.

15. In a car, an underframe comprising built up bolsters, a center sill comprising a cast tension member extending into and forming a part of each of said bolsters, and a compression member formed of rolled 115 metal extending through and beyond said bolsters at each end of the car.

16. In an underframe, bolsters, a truss center sill comprising a compression member formed of a plurality of rolled commercial sections and a cast tension member formed with a bottom flange terminating in proximity to the bolsters and secured at its ends to the compression member and also intermediate of its length by struts 120 cast integral therewith, side sills and cross bearers connecting said center and side sills.

17. A longitudinal trussed sill for railway cars, comprising a compression mem- 130

ber formed of a plurality of rolled commercial sections, a cast tension member having a flange on its lower edge, said tension member being fixed to the compression member at its ends and intermediate thereof by struts cast integral therewith.

18. In an underframe for railway cars, a truss center sill comprising a compression member formed of a plurality of rolled commercial sections, a cast flanged tension member having a supporting web and struts extending from said web intermediate the length of the tension member, the upper edge of the struts being provided with flanges all lying in the same plane for supporting and being fixed to the compression member, side sills and cross bearers connecting the side and center sills.

19. In an underframe for railway cars, the combination of a longitudinal truss comprising a compression member formed of a plurality of rolled commercial sections and a cast tension member, transverse members transmitting their weight to the cast tension member and side sills carried by said transverse members.

20. In an underframe for railway cars, the combination of a longitudinal truss comprising a compression member formed of a plurality of rolled commercial sections and a cast tension member, cross members secured together through the compression member and secured thereto and transmitting their weight to the cast tension member and the weight of their load to the compression member, side sills carried by said cross members.

21. In an underframe for railway cars, a center sill comprising a compression member formed of a plurality of rolled commercial sections, a cast tension member, bolsters and cross bearers carried by said center sill, side sills carried thereby, draft sills carried by said bolsters and center sills, and end sills carried by the side and draft sills.

22. In an underframe for railway cars, a center sill comprising a compression member formed of a plurality of rolled commercial sections, a cover plate secured thereto, a cast tension member, bolsters and cross bearers carried by said center sill, side sills carried thereby, draft sills carried by said bolsters and center sills, and end sills carried by the side sills and draft sills.

23. In an underframe for railway cars, a center sill comprising a compression member formed of a plurality of rolled commercial sections and a cast tension member, said compression member being provided with a cover plate and with angle iron reinforcements at the point of juncture with the tension member, bolsters and cross bearers carried by said tension member and secured to the compression member, side sills carried by said cross bearers, draft sills sup-

ported by the tension member and fixed to the compression member, and end sills carried by the draft sills and side sills.

24. In an underframe for railway cars, a center sill comprising a compression member formed of a plurality of rolled commercial sections and a cast tension member provided with a web and a flange along the underside of said web, bolsters and side bearers supported by said tension member and secured to the compression member, side sills supported by said cross bearers, draft sills supported by and secured to the center sill and end sills supported by and secured to the said draft sills and side sills.

25. In an underframe for railway cars, a center sill comprising a compression member formed of rolled commercial sections, a cast tension member provided with a web and a flange supported by said web, flanged recesses within the web forming struts adapted to support the compression member, bolsters and cross bearers secured to the said center sill, side sills supported thereby, draft sills supported by and attached to said center sills and end sills supported by the draft and side sills.

26. In an underframe for railway cars, a center sill comprising a compression member formed of rolled commercial sections, a cast tension member extending beyond the bolsters, a king pin socket and bolster filler integral therewith, a web for the said casting supporting a bottom flange, a flanged recess in said web forming struts adapted to support the compression member, bolsters and side bearers carried by said center sill, side sills supported by said cross bearers, draft sills carried by said center sills, and end sills supported by said draft and side sills.

27. In an underframe for railroad cars, the combination with bolsters and side bearers, of a center sill comprising a compression member formed of a plurality of rolled commercial sections, a cast tension member formed with a web provided with a flange along the bottom thereof, a flanged recess in said web forming struts adapted to support said compression member, horizontal flanges projecting from the said tension member and adapted to support the bolster and wings carrying brackets adapted to support the cross bearers, side sills carried by said cross bearers, draft sills carried by said center sill and end sills carried by said draft sills and side sills.

28. In an underframe for railway cars, the combination of bolsters and cross bearers, of a center sill, comprising a compression member formed of a plurality of rolled commercial sections, a cast tension member extending beyond the bolsters, a king pin socket and bolster filler cast integral therewith, the web of the casting being provided

with a flange along the bottom thereof and with horizontal integral flanges extending therefrom adapted to support the bolster sections and with vertical integral wings extending therefrom and carrying suitable brackets adapted to support the cross bearers, side sills supported by and attached to said bolster and cross bearers, draft sills attached to and carried by said center sills, and end sills attached to and carried by said draft and side sills.

29. In an underframe for railway cars, the combination of bolsters and draft sills and cross members, of a center sill comprising a compression member formed of a plurality of rolled commercial sections, a cast tension member extending beyond the bolsters, a king pin socket and bolster filler cast integral therewith, the web of the casting having a flange extending along the bottom thereof and having horizontal integral flanges extending therefrom and adapted to support the bolster sections and vertical wings extending therefrom and carrying suitable brackets adapted to support the cross bearers, vertical end flanges extending beyond the bolsters and adapted to support the draft sills, side sills supported and fixed to said bolsters and cross bearers and end sills supported and fixed to said side and draft sills.

30. An underframe for railway cars, a center sill comprising a compression member formed of a plurality of rolled commercial sections and a cast tension member, a cast bolster attached to and carried by said center sills, side sills attached to and supported by said bolsters and cross bearers, draft sills support and fixed to said center sills, and end sills supported and attached to said side and draft sills.

31. In an underframe for railway cars, a center sill comprising a compression member formed of a plurality of rolled commercial sections, a cast tension member, a cast bolster provided with an upper and lower flange and a connecting web provided with a flange arranged in two planes and adapted to conform to the contour of the center sill and means attached to the bolster sections and extending through the compression members for securing the bolster sections together, cross members intermediate of the bolsters supported by the center sill and side sills and fixed to said cross members and bolsters.

32. In a car underframe, a center sill comprising a compression member formed of a plurality of rolled commercial sections and a cast tension member, bolsters, rolled metal cross members provided with an inclosing flange the end thereof being arranged in two planes and adapted to conform to the contour of the center sill and side sills attached to and carried by said bolsters and cross members.

33. In an underframe for railway cars, a center sill comprising a compression member formed of a plurality of rolled commercial sections and a cast tension member, bolsters, rolled metal cross bearers provided with a surrounding flange the end section of which is arranged in two planes to conform to the contour of the center sills, a tapered tie-plate attached to the said cross bearers and extending through and being attached to the compression member, side sills fixed to and carried by said bolster and cross bearers.

34. In an underframe for railway cars, a center sill comprising a compression member formed of a plurality of rolled commercial sections and a cast tension member, bolsters, rolled metal cross bearers provided with a surrounding flange, the end section of which is arranged in two planes to conform to the contour of the center sill, a tapered tie plate attached to the said cross members, and extending through and attached to the compression member, an angle brace provided with an upstanding flange on the end of said cross bearer and a side sill adapted to be attached to and carried by said cross bearer and bolsters.

35. In an underframe for railway cars, a center sill formed of a plurality of rolled commercial sections, a cover plate therefor, a cast tension member, draft sills supported by said tension member and secured to the compression member, the said cover plate extending over and being secured to the said draft sills, transverse members, a side sill supported by said transverse members, and an end sill supported by said draft and side sills.

In witness whereof I have hereunto set my hand in the presence of two witnesses.

JOHN M. ROHLFING.
